UNITED STATES PATENT OFFICE.

JAMES WILKINSON, OF LYNN, MASSACHUSETTS, ASSIGNOR TO GENERAL ELECTRIC COMPANY, A CORPORATION OF NEW YORK.

STRAINER.

Application filed April 25, 1925. Serial No. 25,896.

The present invention relates to strainers such as are used in connection with steam pipe lines for example, to prevent foreign articles being carried through the pipe line. 5 For instance, it is the practice to provide a steam strainer in the pipe line conveying steam to a turbine, and this is one use to which my invention is well adapted.

The ordinary wire strainer commonly used possesses the disadvantage that when made of wire of a strength sufficient to afford the required protection, it presents openings for flow through it equal to but about $\frac{1}{3}$ of its total area. In other words, 15 its effective flow area is equal to about $\frac{1}{3}$ its overall area. As a result, in placing such a strainer in a pipe line, it is necessary to provide a strainer of a diameter considerably greater than the diameter of the pipe 20 line in order to obtain the required area of opening. For example, in the case of an 18 inch pipe, it is necessary to provide a wire strainer of the order of 30 inches diameter to provide the necessary flow area. 25 This means that a large strainer casing must be provided and also one of considerable length so as to properly direct the steam to and from the strainer. Even then there is considerable loss in such a strainer.

30 The primary object of my invention is to provide an improved strainer which will give the required total effective flow area and which will have the required strength while at the same time it need be but little 35 larger in diameter than the pipe line with which it is to be used.

A further object of my invention is to provide an improved strainer wherein the loss due to flow through it is reduced to a 40 low value.

For a consideration of what I believe to be novel and my invention, attention is directed to the accompanying description and the claims appended thereto.

45 In the drawing, Fig. 1 is a longitudinal sectional view of a strainer embodying my invention; Fig. 2 is a transverse sectional view thereof; Fig. 3 is a perspective view on a large scale of a part of the strainer, 50 and Fig. 4 is a detail sectional view on a still larger scale of one of the cross plates.

Referring to the drawing, 5 indicates a strainer casing having flanges 6 enabling it to be bolted into a pipe line. In it is an 55 opening 7 through which the strainer is in-

serted, the opening being closed by a cover plate 8 fastened in position by bolts 9.

The strainer comprises a rim 10 within which are two sets of strips 11 and 12 which extend at a right angle to each other. The 60 strips 12 are provided with notches or slots 13 in which strips 11 fit. These notches are of a depth such that the strips overlap each other but part way, the strips 11 projecting beyond strips 12 on the up stream side of 65 the strainer, and the strips 12 projecting beyond strips 11 on the down stream side of the strainer. In the present instance, strips 11 are shown as being made of thicker material than strips 12 and certain of them, 70 as is indicated at 14, are made of greater width than the others to give strength to the structure. The strips may be fastened together and to rim 10 in any suitable manner. Preferably I connect them together 75 by fused metal, for example by brazing or welding, as this gives a strong unitary structure. In casing 5 is a groove 15 in which rim 10 fits, the inner edge of the rim being flushed with the surface of the casing. The 80 up stream edges of strips 11 are rounded so as to direct the flow smoothly, and the down stream edges of strips 12 are sharpened as shown particularly in Fig. 4.

With the above described arrangement, 85 it will be seen that there are provided a multiplicity of cellular passages and that these passages are smallest in the region where the strips overlap, i. e., at their central portions, and are of greater area in 90 advance of and beyond such central portions. This, as will be clear, is due to the fact that the strips overlap each other but part way. As a result, there is provided through the strainer multiple Venturi 95 shaped passages, and because of their Venturi shape, they effect the passage of the steam with but little loss, reconversion of velocity into pressure taking place between the discharge edges of plates 12. 100

Because of their width, strips 11 and 12 may be made of comparatively thin stock and still give the required strength. For example in certain cases, I have found it satisfactory to make strips 11 of material 105 $1/32''$ thick and strips 12 of material $1/64''$ thick. Preferably the notches 13 are punched in the strips of the thinner material for manufacturing reasons although they may be otherwise arranged. 110

With the above described arrangement, I have found that I can produce a strainer having an effective flow area, that is, a total passage area, equal to about 75% of the area 5 of the strainer. As a result a strainer embodying my invention need be not nearly so large as in the case of an ordinary wire strainer. Taking for example the case of a strainer for an 18 inch pipe as hereinbefore referred to, a strainer for this size pipe embodying my invention need have a diameter of only about 22 inches as opposed to a strainer of the order of 30 inches diameter when made of wire after the ordinary manner. 15 As a result, my improved strainer is much smaller in size. Furthermore, because of its Venturi shaped passage, it introduces a much smaller loss into the pipe line. Also, since my improved strainer is required to be of a diameter but little greater than the pipe diameter in which it is used, I am enabled to provide a much smaller angle of approach to and recession from the strainer without increasing the length of the strainer 20 casing. For example, in the case of fluid flow through a diverging pipe section, the angle of the diverging section should be ordinarily not greater than 7 degrees to obtain the best results. By my invention, I am enabled to use an angle of this order and still need only a comparatively short strainer casing, and in the drawing, Fig. 1, it will be noted that the angle of approach to and recession from the strainer proper is of such 25 low value. This functions to minimize the losses in the strainer.

In accordance with the provisions of the patent statutes, I have described the principle of operation of my invention, together 30 with the apparatus which I now consider to

represent the best embodiment thereof; but I desire to have it understood that the apparatus shown and described is only illustrative and that the invention may be carried out by other means. 45

What I claim as new and desire to secure by Letters Patent of the United States, is:

1. A strainer comprising two sets of thin flat strips, the strips of one set crossing the strips of the other set and said sets of strips 50 partially overlapping each other whereby on each side of the strainer the edges of one set of strips project beyond the adjacent edges of the other set of strips.

2. A strainer comprising sets of thin flat 55 strips arranged crosswise relatively to each other and partially overlapping each other, whereby on each side of the strainer the edges of one set of strips project beyond the edges of the other set of strips, the projecting edges on the down stream side of the strainer being tapered toward their free 60 ends.

3. A strainer comprising a peripheral retaining member and transversely extending 65 thin flat strips mounted therein, said strips crossing each other and partially overlapping so as to form passages smaller in cross sectional area at their central portions than at their ends.

4. A strainer comprising a holding member, a set of thin flat strips therein, and a second set of thin flat strips which crosses the first named set and is fastened thereto by fused metal, said strips having notches 70 whereby the strips of one set partially overlap the strips of the other set.

In witness whereof, I have hereunto set my hand this 23rd day of April, 1925.

JAMES WILKINSON.
